The ornamental design for a universal projector mount, as shown and described.

DESCRIPTION

FIG. 1 is a front perspective view of a universal projector mount according to the invention;

FIG. 2 is a top plan view of the universal projector mount depicted in FIG. 1;

FIG. 3 is a bottom plan view of the universal projector mount depicted in FIG. 1;

FIG. 4 is a front elevation view of the universal projector mount depicted in FIG. 1;

FIG. 5 is a side elevation view of the universal projector mount depicted in FIG. 1;

FIG. 6 is a rear elevation view of the universal projector mount depicted in FIG. 1; and,

FIG. 7 is an opposing side elevation view of the universal projector mount depicted in FIG. 1.

The broken lines immediately adjacent to the shaded areas represent the bounds of the claimed design while all other broken lines are included for the purpose of illustrating environmental structure only; the broken lines form no part of the claimed design.
